Patented Apr. 23, 1912.

UNITED STATES PATENT OFFICE.

CLARENCE M. CORLEW, OF SIOUX FALLS, SOUTH DAKOTA, ASSIGNOR OF ONE-THIRD
TO JOHN MUNDT, OF SIOUX FALLS, SOUTH DAKOTA.

RAIL-JOINT.

1,024,313.

Specification of Letters Patent. Patented Apr. 23, 1912.

Application filed June 14, 1911. Serial No. 633,160.

To all whom it may concern:

Be it known that I, CLARENCE M. CORLEW, citizen of the United States, residing at Sioux Falls, in the county of Minnehaha 5 and State of South Dakota, have invented certain new and useful Improvements in Rail-Joints, of which the following is a specification.

The present invention comprehends certain new and useful improvements in rail joints, and the object of the invention is to unite the meeting ends of companion rail sections in an improved manner so as to provide a joint which possesses to a marked 15 degree the characteristics of simplicity, durability and strength, and which affords a continuous tread surface in order to eliminate the usual pounding of the wheels of the rolling stock as they pass over the joint.

Another object of the invention is to provide rail sections formed at their meeting ends with overlapping tongues which have an interlocking engagement for the purpose of holding the meeting ends of the rail sections against both longitudinal separation 20 and relative vertical displacement.

With these and other objects in view, as will more fully appear as the description proceeds, the invention consists of certain 30 constructions, arrangements and combinations of the parts that I shall hereinafter fully describe and claim.

For a full understanding of the invention, reference is to be had to the following 35 description and accompanying drawing in which:

Figure 1 is a sectional perspective view of my improved rail joint; Fig. 2 is a transverse section thereof; Fig. 3 is a detail perspective view of the meeting end of one of the rail sections; and, Fig. 4 is a horizontal 40 longitudinal section illustrating another embodiment of the invention.

Corresponding and like parts are referred 45 to in the following description and indicated in all the views of the drawing by the same reference characters.

My improved rail joint is shown and described in connection with a pair of companion rail sections 1, each of which comprises a head 2, web 3 and a base flange 4, and is of conventional form except at its meeting end where the web is thickened, as indicated at 5, so as to be flush with both 55 sides of the head. The thickened ends of

the rail sections are cut away on opposite sides of the rail and throughout the full height thereof, in order to provide longitudinally projecting tongues 6 and longitudinally facing shoulders 7 against which the ends of the tongues are adapted to abut. The tongues overlap each other with the end of each tongue arranged in abutting relation to the shoulder 7 at the inner end of the other tongue, thereby providing a 65 scarf joint.

The tongues are substantial duplicates and are designed to interlock to retain the rail sections in association. For this purpose each tongue is formed with two longitudinally disposed lugs 8 and 9 projecting from its inner face. The lugs are approximately half as long as the tongue, and the lug 9 extends from the shoulder 7 approximately to the middle point of the tongue, 70 while the lug 8 extends from said middle point to the terminal of the tongue. The lug 8 has its upper edge flush with the tread surface of the rail and its lower edge spaced above the base of the rail to form a downwardly facing shoulder 10. The upper edge of the lug 9 lies in the same plane as the shoulder 10 and provides an upwardly facing shoulder 11, the lower edge of the lug 9 being flush with the plane of the base 85 of the rail. The lugs 8 and 9 are, therefore, located at diagonally opposite corners of the inner face of the tongue. Between these lugs there are provided, in effect, seating recesses 12 at the remaining corners of the inner face of the tongue, for the reception 90 of the lugs of the mating tongue. Bolts 13 are inserted through transversely registering openings 14 to retain the tongues in engagement with each other. 95

It will be noted that the lug 8 of each tongue fits over the lug 9 of the other tongue and is received in the seating recess 12 between the shoulder 7 and lug 8 of the said other tongue. The inner ends of the lugs 8 are thus arranged in abutting relation, whereby to prevent the rail sections from being separated longitudinally. Of course the lugs may be made slightly shorter than the seating recesses in order to have sufficient play therein to compensate for expansion and contraction. Another important feature resides in the fact that each shoulder 10 rests upon the upwardly facing shoulder 11 of the opposite tongue, so that the 110

tongues mutually support each other to resist any relative vertical displacement. By this means the rail sections are securely connected together without the use of the customary fish plates. Furthermore the joint is rendered quite solid by having the web portions of the meeting ends of the rail sections thickened flush with the sides of the heads.

10 In practice it sometimes becomes necessary to couple a rail section 1 having a terminal tongue 6 of the form above described, with a rail section 15 of the ordinary type. In order to enable this to be accomplished without breaking the continuity of the tread surface, I provide a filler member 6^a which is separate from both rail sections and is similar to the tongue 6 and is adapted to interlock therewith. The filler member 6^a fills 15 up the cutaway portion in the side of the rail section 1 so that the meeting end of this rail section is of substantially conventional form except that its web is thickened flush with the sides of its head. The joint 20 between the rail sections may therefore be effected by employing fish plates 16 which lie against opposite sides of the webs of the rail sections and are secured thereto by bolts 17, the difference in thickness of the webs 25 being compensated for by offsetting the fish plates at intermediate points, as indicated at 18. The bolts 17 passing through the rail section 1, serve to hold the separate filler member 6^a in association with the tongue 6

so that no additional fastening devices need 35 be employed for this purpose.

Having thus described the invention, what I claim as new is:

1. A rail section formed at one end with a longitudinal tongue, and locking members 40 rigid with and projecting from the inner face of the tongue at diagonally opposite corners thereof, the tongue being formed at the remaining corners of its inner face with seating recesses for the reception of the 45 members of the mating tongue.

2. A rail section formed at one end with a longitudinal tongue and locking members rigid with and projecting from the inner face of the tongue at diagonally opposite 50 corners thereof, the tongue being formed at the remaining corners of its inner face with seating recesses, a filler member conforming to one of the tongues and provided with projections at its diagonally opposite corners to seat in the seating recesses of said tongue, and clamping devices bearing upon opposite sides of the tongue and filler member and extending in advance of the same 55 and adapted to bear over the adjacent portion of an abutting rail.

In testimony whereof, I affix my signature in presence of two witnesses.

CLARENCE M. CORLEW. [L. S.]
